SAG INDICATOR

Francis A. E. Koski, Snow Shoe, Pa.

Application June 1, 1951, Serial No. 229,433

4 Claims. (Cl. 116—114)

My invention relates broadly to mine safety appliances and more particularly to a sag indicator which may be installed in the roofs of mines for indicating the progressive condition of sag in order to predetermine any dangerous condition of mine roof failure.

One of the objects of my invention is to provide a construction of sag indicator which may be installed in mine roofs at various levels below the earth for providing accurate means for inspection and measurement of any change in sag of the mine roof for providing a predictable indication of dangerous conditions of roof failure.

Another object of my invention is to provide a construction of warning indicator for mine roofs which may be readily installed in a mine roof in a manner in which the indicator is reliable for sounding an alarm under conditions of dangerous sagging of the roof for enabling preventative measures to be taken at very early stages of roof sagging for avoiding collapse of the roof.

Another object of my invention is to provide a construction of sag indicator which is so inexpensive that large numbers of such indicators may be installed in various parts of the roof structure of a mine for enabling periodic inspections to be made of sagging conditions of the roof for predicting dangerous conditions of the roof and enabling precautionary measures to be taken for preventing roof failure by the installation of supplemental timbers or bracing means.

Still another object of my invention is to provide a simplified construction of calibrated sag indicator for installation in mine roofs by which a calibrated indicator may be inspected from time to time for predetermining the condition of sag of the mine roof to enable preventative measures to be taken at the very early stages of any indication of mine roof failure.

Still another object of my invention is to provide an arrangement of dependable electric circuit closer which is operative under conditions of sag of a mine roof for sounding an alarm for providing an indication of dangerous roof condition to enable proper reinforcement to be made at indicated dangerous locations in the mine for improving mine safety conditions.

Other and further objects of my invention reside in a simplified construction of sag indicators for installation in mine roofs as set forth more fully in the specification hereinafter following by reference to the accompanying drawings in which:

Figure 1 illustrates a coacting pair of sag indicators constructed in accordance with my invention and installed in spaced positions transversely of the center of a mine roof in positions where shear slippage or sagging adjacent the center of the roof may differentially affect either of the sag indicators; Fig. 2 is a view looking upwardly of the floor of the mine and showing the sag indicators in installed position in the roof of the mine; Fig. 3 is a horizontal sectional view taken on line 3—3 of Fig. 1; Fig. 4 is an enlarged view similar to the view shown in Fig. 1 but illustrating a condition of sag in the mine roof and the manner in which this condition is at

2

once made apparent upon inspection of the sag indicator of my invention; Fig. 5 shows a modified form of the device for measuring sag constructed in accordance with the principles of my invention, the resilient means for separating the measuring plates being omitted in this instance for purposes of simplification; Fig. 6 is a perspective view of one of the measuring plates used in the form of sag indicator illustrated in Figs. 1—5; Fig. 7 is a perspective view of a modified form of one of the measuring plates; Fig. 8 is a plan view of a form of resilient separator which may be employed for initially maintaining the measuring plates in spaced relation; Fig. 9 is a transverse sectional view taken on line 9—9 of Fig. 8; Fig. 10 is a plan view of a further modified form of resilient separator for the measuring plates; Fig. 11 is a side elevational view of the spring separator shown in Fig. 10; Fig. 12 is a vertical sectional view taken through a further modified form of sag indicator of the self-indicating type in which an indicating needle is displaced over a calibrated scale in accordance with displacement of the position of the measuring plates under varying conditions of sag, the resilient means for maintaining the measuring plates in spaced relation being also omitted in this instance for purposes of simplification; Fig. 13 is a vertical sectional view taken on line 13—13 of Fig. 12; Fig. 14 is a schematic and diagrammatic view with parts broken away and shown in section and illustrating an electric alarm signal controlled by the sag indicator; Fig. 15 is an enlarged vertical sectional view of the electric alarm device illustrated in Fig. 14 and showing the components by which an electric circuit is closed due to conditions of sag of the mine roof structure; Fig. 16 is a transverse sectional view taken on line 16—16 of Fig. 15; Fig. 17 is a horizontal sectional view taken on line 17—17 of Fig. 15; Fig. 18 is a view illustrating the condition resulting from sagging of the roof structure and the closing of an electrical circuit through the contact members associated with the form of my invention illustrated in Figs. 14—17; Fig. 19 illustrates a further modified form of sag indicator embodying my invention; and Fig. 20 is a perspective view of the measuring element employed in the form of my invention shown in Fig. 19.

My invention is directed to safety systems for mines in which dangerous conditions of roof failure may occur without knowledge or warning and the failure reach such proportions that remedial steps for reinforcement of the mine roof may be too late. The hazards of roof failure are continually increased in mines due to blasting in adjacent areas and conditions of shear and sag in the roof often reach dangerous proportions before the slippage is discovered bringing about a condition of great peril to the mine workers. It is recognized that mine roofs do not fail without warning and if a warning can be given sufficiently in advance of a dangerous condition of sag ample time is available for the erection of supporting timbers or beams or suspension rods for bracing or reinforcing the roof to prevent failure. The sag indicator of my invention greatly simplifies detection and measurement of roof sag. My invention provides means for indicating the rate at which the sag may be progressing and thus allows the condition of the invisible layers. The indicator of my invention shows the extent of the roof fall in time to allow preventative measures to be taken such as the timbering or the installation of suspension rods and allows for their economical installation by determining the amount of reinforcement required to prevent sag. The sag indicator of my invention is not limited to applications of mining but can be used in construction work generally such as in connection with concrete forms and the like. The sag indicator is constructed in multiples so that the condition of one indicator may be compared to the condition of an adjacent indicator. Each

indicator comprises a suspension rod which is anchored into the strata of the mine roof or the material of a beam. The suspension rod carries a pair of measuring plates having means therebetween for normally separating the plates. A variety of different means may be employed for this purpose, such as coil springs, compressible, resilient or yieldable material and/or leaf springs. These spring devices normally tend to maintain the measuring plates in predetermined spacial relation. However, conditions of sag in one area of a roof or beam structure 10 may affect movement of one measuring plate toward a coacting measuring plate differently than conditions existing with respect to the measuring plates of an adjacent indicator. This differential distance is readily measurable to indicate the conditions which may be predicted with 15 regard to displacement in the invisible strata of a mine roof structure for thereby indicating dangerous conditions of sag. In certain instances the indicator is calibrated to show the progressive movement in the invisible strata of the roof structure. In other instances the separator 20 between the measuring plates includes electrical contactors which may be displaced to close an electrical circuit and thereby supply a warning alarm. All of these indication means enable remedial steps to be taken for reinforcement of the mine roof structure for preventing further sagging at dangerous locations.

Referring to the drawings in more detail reference characters 1, 2, 3, 4, 5, 6, 7 and 8 in Fig. 1 indicate the strata constituting a mine roof, the superimposed layers of which are subject to sagging, slippage and shear and into which the holes 11 and 12 are drilled. These drill holes are generally selected in substantially the center of the span of the roof structure in a mine where conditions of sag are most likely to occur. Suspension rods 14 and 15 are driven into the drilled holes 11 and 12. The suspension rods are each provided with a spike end as represented at 14a and 15a for accurately fastening the suspension rods in the strata of the roof structure. The suspension rods are screw threaded on the ends thereof as represented at 14b and 15b. A measuring plate 16 is slipped over the screw threaded end of suspension rod 14 and is loosely retained on the suspension rod while the compressible member such as a coil spring, a leaf spring or a compressible block of material is vertically moved into position over the suspension rod. In the form of 45 my invention illustrated in Figs. 1-4 this compressible member is in the form of a coil spring 17. The coil spring is retained in position by means of a measuring plate 18 which is slipped over the end of the suspension rod 14 within the limits of the screw threaded portion 14b of the suspension rod. An adjustable securing nut 19 is engaged over the screw threads 14a on the end of the suspension rod 14 for confining the compressible member 17 between the measuring plates 16 and 18. Tension is applied to the compressible member 17 by initially adjusting nut 19 to a position in which the initial measurement as the device is installed may be determined by the distance A as shown in Fig. 4. A suitable lock nut may be applied to the threaded end 14b of suspension rod 14 for insuring the precision maintenance of the initial setting of the spacial relation of the measuring plates.

On the adjacent suspension rod 15 with which the measurements revealed by the spacial relation of the measuring plate 16 and 18 on suspension rod 14 are to be compared, I provide a similar arrangement of measuring plates spacially separated by a substantially identical compressible member and secured in position by a suitable nut. This arrangement is shown at the right of Figs. 1 and 4 of the drawings where the measuring plate which directly contacts the lowermost strata of the mine roof is indicated at 20 loosely fitting over suspension rod 15 and maintained in position by compressible member 21 against which measuring plate 22 is confined by means of suitable nut 23 engaged over screw threads 15a on the end of the suspension rod 15. The compressible mem-

bers 17 and 21 and all of the associated parts of the sag indicators are held within close tolerances so that operating characteristics for all indicators are substantially the same. The spacial distance between measuring plates 20 and 22 is initially set to be identical with the spacial distance between measuring plate 16 and 18 of the adjacent indicator when installed. The sag indicators when installed may continue to show the same spacial distance between measuring plates 16 and 18 and measure plates 20 and 22, for example, for all normal conditions in the roof seams 1-8 in Fig. 1 or 1-10 in Fig. 4. The spacial distance between measuring plates 16 and 18 or between measuring plates 20 and 22 may be checked from time to time with a suitable measuring device such as a caliper or appropriate scale and for all normal conditions there may be no variation in the spacial relation of the measuring plates as revealed by these periodic checks and measurements.

However, as shown in Fig. 4 sagging may occur in the roof seams 3, 4, 5, 6, 7, 8, 9 and 10, to the right of the center of the roof span and a shearing may occur along the center line designated at 24 in Fig. 4 insuring in the dropping of an unsupported area of the roof structure with respect to the supported area of the roof structure as shown in Fig. 4. This sagging may or may not be observable to the eye but produces a displacement of the roof seams for a distance indicated by distance C in Fig. 4. This slippage results in the movement of measuring plate 20 toward measuring plate 22 on suspension rod 15 within the unsupported area of the mine roof resulting in compression of the compressible member 21 so that measuring plates 20 and 22 approach each other to the distance B. Thus a perceptible difference in spacial relation between measuring plates 16 and 18 and measuring plates 20 and 22 is readily observable by measurement of the distance B between measuring plates 20 and 22 as compared to the distance A between measuring plates 16 and 18. Upon discovery of the differential measurement remedial measures may be taken to reinforce the unsupported area of the mine roof by timbering, bracing, and/or the installation of additional suspension rods for reinforcing the roof and preventing further sagging. It is readily apparent that without such a precautionary indicator as provided by my invention sagging of the mine roof in various areas might go unnoticed and only be discovered after a condition bordering upon collapse of the mine roof exists which might be too late for correction.

Various arrangements of measuring means may be provided and in Fig. 5 I have illustrated an arrangement in which the measuring plates 20 and 22 supported on suspension rod 15 are each provided with precision measuring points 20a and 22a which are screw threaded or riveted into the measuring plates 20 and 22 in aligned positions adjacent one edge thereof. The measuring points 20a and 22a serve as surfaces between which the measuring arms 25 and 26 of a suitable telescopic micrometer gage 27 may be inserted. The micrometer gage 27 carries appropriate calibrations 28 on the adjustable scale thereof by which the spacial relation of the arms 25 and 26 which pivot about center 29 are made quickly available. Thus the spacial distance between measurement plates 20 and 22 may be quickly checked at each of the indicator installations and differences in the spacial relation of the measuring plates quickly detected. For purposes of simplification, I have omitted the arrangement of compressible member between measuring plates 20 and 22 in Fig. 5 but it will be understood that such compressible member may be a coil or leaf spring or a spacer formed from resilient or yieldable material.

In Fig. 6 I have shown in perspective view the form of measure plate 16 which may be employed in the indicator of my invention. Fig. 7 shows still another form of measuring plate such as circular plate 30 which may be employed in the sag indicator of my invention.

In Figs. 8 and 9 I have shown a construction of resilient

or yieldable block 31 which may be used as a separator between the measuring plates in the sag indicator. This block may be formed from rubber or yieldable synthetic composition sufficient to maintain the normal spacial relation of the measuring plates but sufficiently yieldable to allow displacement of the material under conditions of compressive force.

Figs. 10 and 11 show a form of leaf spring which I may employ in association with the suspension rod as a spacing device for the measuring plates on the suspension rod in lieu of the coil spring of Figs. 1-4 or the block of Figs. 8 and 9. I have shown the leaf spring at 32 having a central elevated portion apertured at 32a for the passage of the suspension rod and having a pair of outwardly extending downwardly directed spring arms 32b and 32c. The central portion of the leaf spring bears against the upper measuring plate while the spring arms 32b and 32c bear against the bottom measuring plate for yieldably maintaining the measuring plates in separated relation throughout the period when the upper measuring plate is approaching the lower measuring plate under conditions of sag.

In Figs. 12 and 13 I have shown a sag indicator embodying my invention where the indicator is of the self-indicating type. In this arrangement the suspension rod 15 is shown extending through measuring plates 20 and 22 in a position below the roof structure 9-10 of the mine or other structure in which the condition of sag is to be detected. The terminating end of the suspension rod 15 is screw threaded as shown at 15b and is engaged by nut 23 for maintaining measuring plate 22 in position. The measuring plate 22 carries the vertically extending indicator plate 33 which is welded at its lower edge to the upper face of measuring plate 22 as represented at 34. The indicator plate 33 carries a calibrated scale 35 thereon which is graduated to show various conditions of sag directly observable by movement of the pointer 36 over scale 35 as the condition of sag increases. Pointer 36 is pivotally mounted in the upper left-hand corner of indicator plate 33 as represented at 37 and is provided with an extension 38 thereon with an upwardly extending projection which establishes tangential contact with the undersurface of measuring plate 20. A lever arm is thus provided between the extension 38 of the pointer 36 and the central pivot 37 so that as measuring plate 20 approaches the limiting edge 33a of the indicator plate 33 pointer 36 is moved over the range of the calibrated scale 35 visually indicating the condition of sag in the mine roof. It will be understood that the compression coil spring such as coil spring 21 of Figs. 1-4, or the resilient spacer 31 of Figs. 8 and 9 or the leaf spring 32 of Figs. 10 and 11 is provided in the structure of Figs. 12 and 13 for maintaining the measuring plates 20 and 22 in spaced positions so that measuring plate 20 will follow the actual sag condition of the mine roof or other structure.

In Figs. 14-18 I have illustrated another embodiment of my invention in which an electrical circuit is closed for sounding an alarm under conditions of sagging of the mine roof or other structure. In this arrangement a resilient body 39 is provided for normally spacing the measuring plates 20 and 22 where the suspension rod 15 passes through the resilient body 39. The resilient body 39 is vertically apertured adjacent one side thereof as represented at 40 for receiving spaced contact plugs 41 and 42. The spaced contact plugs snugly fit into the resilient bore 40 and are provided with contact faces 41a and 42a thereon which are normally spaced apart under normal and safe conditions with respect to roof sag such as the condition illustrated in Figs. 14-16. The contact plug 41 connects through electrical conductor 43 insulated as shown at 44 and electrically connected to an alarm circuit represented at 45 in Fig. 14 including the electric signal device 46, and a source of potential 47 electrically connected to ground as represented at 48. The contact

plug 42 which is normally spaced from contact plug 41 is electrically grounded on measuring plate 22 through the metallic confining nut 23 and suspension rod 15 to the ground connection 49. Under all normal conditions where there is no dangerous tendency for mine roof sag the contact faces 41a and 42a of plugs 41 and 42 are spaced apart as represented at Figs. 14-16 for all safe conditions of the roof structure represented by the dimension X in Fig. 16. Under conditions of dangerous sag of the roof structure measuring plate 20 moves toward measure plate 22 compressing the resilient body 39 to the dimension Y as represented in Fig. 18 thereby compressing contact plug 41 with respect to contact plug 42 closing an electrical circuit through contact faces 41a and 42a and through the grounded return path 49-48 for operating the electric signal device 46. To facilitate the establishment of a good electrical connection between contact plug 42 and the measuring plate 22 the contact plug 42 is provided with a conical shaped end 42b which tends to enter the surface of measuring plate 22 insuring a good electrical connection therewith. Thus the approach of measuring plate 20 toward measuring plate 22 under conditions of dangerous sag is detected by the sounding of either an audible or a visual alarm by electrical action.

In the several forms of my invention the confining nuts 19 and 23 have been indicated as engaging the screw threaded ends of the suspension rods. It is to be understood that lock nuts may be provided in these positions to prevent shocks or vibration from dislodging the nuts 19 and 23 and thus impairing the operation of the indicator of my invention.

Figs. 19 and 20 illustrate a form of my invention in which the measuring plates are omitted and a resilient strip 50 bent into the shape of a U with the flat ends of the two arms thereof provided with apertures 51 and 52 which when aligned permit the bent strip to be positioned over the depending end of the suspension nut 15b, so that the projecting ends of the two arms of the strip 50 are free to be compressed toward each other as the structure, such as 7, 8, 9, and 10, develops a condition of sag. The upper flat face of the top arm of the U shaped strip 50 directly bears against the lower surface of the strata 10 and is bent toward the lower flat face of the lower arm as the strata 10 is displaced downwardly. The distance 53 between the projecting ends of the arms of the strip may accordingly be measured to determine the condition of slippage of the structure 7, 8, 9, and 10. Nut 15b may be initially adjusted on the screw threaded end of the suspension rod 15 for fixing the spacial relation of the ends of the arms of strip 50 to a normal position with respect to which the approach of the ends of the arms may be compared from time to time for determining the amount of sag in the associated structure.

I have described my invention in certain of its preferred embodiments but I realize that modifications in structure and arrangement may be made and I desire that it be understood that no limitations upon my invention are intended other than may be imposed by the scope of the appended claims.

What I claim as new and desire to secure by Letters Patent of the United States is as follows:

1. A sag indicator comprising a suspension rod adapted to be anchored in a structure for which the condition of sag is to be determined and projected downwardly therefrom beyond the lower surface of the structure, a U shaped resilient strip bent upon itself and having aligned apertures therein adapted to be positioned over the depending end of said suspension rod with the upper surface of one arm in contact with the surface under observation for the condition of sag, and means attached to said rod for confining the position of the other arm of said U shaped strip whereby the ends of the arms of said strip approach each other as the condition of sag in the structure under observation increases.

2. A sag indicator as set forth in claim 1, in which the terminating end of said rod is screw threaded and wherein said threads are engaged by a screw threaded nut adjustable against the bottom surface of the lower arm of said strip for initially setting the spatial relation of the ends of said arms and for subsequently observing the approach of the ends of said arms for correspondingly determining the condition of sag of said structure.

3. Apparatus for warning of failure of a roof having an opening extending upwardly therein comprising, a 10 rod having its upper end secured to the roof at the inner end of said opening and its lower end terminating adjacent the outer end of said opening, a bowed resilient strip of material having free lineally disposed ends extending substantially parallel to each other and terminating in substantially lineal end edges and positioned over the depending end of said rod with the bowed portion of said strip projecting laterally with respect to one side of said rod and the free ends of said strip projecting laterally in the opposite direction with respect to the other side of said rod, and means attached to said rod for confining said bowed strip thereon with one of the free ends of said strip maintained in contact with the lower surface

5

of the roof under observation and the other free end of said strip biased to a position against said means, the resiliency of said strip being such that slippage pressure of the roof against the first mentioned free end of said strip operates to move the said free end of said strip in the direction of the other free end thereof whereby the spatial relation of the lineal ends of the free ends of said strip may be observed as a measure of the condition of failure of the roof.

4. Apparatus for warning of failure of a roof as set forth in claim 3 in which said means attached to said rod for confining said bowed strip thereon consists of screw threads and an engaging screw threaded nut adjustable against the bottom surface of the second mentioned free end of said bowed strip for initially adjusting the spatial relation of the free ends of said strip prior to a condition of failure of the roof.
